UNITED STATES PATENT OFFICE.

ANDREW D. WHITTON, OF PHILADELPHIA, PENNSYLVANIA.

CABLE-GRIPPING MECHANISM.

SPECIFICATION forming part of Letters Patent No. 374,767, dated December 13, 1887.

Application filed May 24, 1887. Serial No. 239,250. (No model.)

To all whom it may concern:

Be it known that I, ANDREW D. WHITTON, of Philadelphia, in the county of Philadelphia and State of Pennsylvania, have invented certain new and useful Improvements in Cable-Gripping Mechanism, of which improvement the following is an explicit and exact specification, enabling one skilled in the art to make and construct the same.

10 My invention relates to that class of cable-grips the upper part of which is secured to the body or truck of a tramway-car and extends downward through a continuous slot running parallel with the rails of the track upon which 15 the car runs, said grip being provided with jaws for gripping an endless traveling cable running in a conduit and situated below the level of the road-bed, the jaws being actuated from the platform of the car by means of a 20 hand-lever and appropriate connecting mechanism under the control of the gripman.

Heretofore grips of this description have been secured to the car body or truck in such a manner as to allow for lateral and vertical 25 play, but otherwise have been permanently connected to the same in such a manner that they could only be detached by the removal of bolts, screws, pins, or keys. It frequently occurs that the gripping mechanism becomes 30 jammed and refuses to operate, either through imperfect workmanship, wear and tear of parts, or damage due to rough usage, and even when none of these causes exist the grip occasionally fails to release the cable through the 35 stranding of the latter. Accidents of the most serious character, entailing loss of life and property, have been occasioned by the failure of the grip to free itself instantaneously under the impulse of the gripman's hand. In a much- 40 traveled thoroughfare intercepting other equally frequented avenues—such as occur in any large city—the gripman of a traction-car is kept continually on the alert and finds it frequently necessary to check his car in full career and to bring it to a dead halt within a 45 very few feet. This he effects by opening the grip and applying the brakes simultaneously; but if at this critical juncture the grip fails him and there is no other means of severing the 50 connection between the cable and the car he loses all control over the latter until it meets

with an obstruction having sufficient inertia to rupture the grip-shank or the cable. It is difficult to estimate the possible damage which might result before or at the time of this occurrence.

55 The object of my invention is to prevent such a contingency by providing a simple and effective means of instantly separating the grip from its actuating mechanism and the car 60 without injury to either when the exigencies of the case require such action through the imperfect action of the grip mechanism.

To this end my improvement consists in bifurcating the extremities of the upper part of 65 the grip-frame, so that they may straddle snugly two vertical cylindrical pins or studs dependent, one from a rectangular and the other from a cylindrical horizontal bar. These bars slide horizontally and laterally in rigid 70 bearings or guides upon the truck or car frame, which are respectively rectangular and cylindrical, to conform in section with the bars to which they serve as guides or bearings. The lower ends of the dependent pins are provided 75 with collars or flanges, upon which the cross-head or upper part of the grip-frame rests when in its normal position. The stud-pin dependent from the rectangular bar, by reason of the rectangular shape thereof, is maintained 80 at all times in a vertical position; but the cylindrical bar is capable of rotary motion upon its axis, and consequently the pin dependent therefrom can be swung away from the bifurcated end of the grip cross-head 85 which it supports. A projection upon the cylindrical bar simultaneously throws the rod which connects the grip hand-lever with the gripping device free from the same, thus severing all connections between the car and grip- 90 frame and jaws. Rotary movement is imparted to the horizontal cylindrical bar by means of a hand-lever upon the platform of the car, connected by a horizontal rod with an arm rigidly fixed upon the cylindrical bar 95 before mentioned. The grip thus unsupported falls of its own weight upon the flanges of the slot of the conduit and is dragged away by the cable, while application of the brake immediately stops the car. It is convenient 100 to place the three hand-levers—to wit, the grip, brake, and releasing levers—side by side

upon the platform within immediate reach of the gripman.

The nature of my improvements and the manner in which they are to be carried out 5 and operated will be understood, reference being had to the accompanying drawings, in which—

Figure 1, Sheet 1, is a vertical longitudinal section through the body and frame of an ordinary passenger coach or car, with the grip and my improvements shown in elevation. Fig. 2, Sheet 1, is a horizontal section on the line $\alpha\alpha$ of Fig. 1, with part of flooring of the car broken away, showing a plan view of the working 10 parts of the truck, grip, brake, and releasing devices. Fig. 3, Sheet 2, is a vertical section, on an enlarged scale, of the forward part of car shown in Fig. 1, embodying my improvements; and Figs. 4, 5, and 6, Sheet 2, show details 15 of the lever, lever-stand, and section of cross-head of grip-frame respectively.

A frame or bridge, A, which in the drawings is shown as journaled upon the axles of the car-wheels, but which may be secured to 20 the car-body, carries two transverse bars, $a\ a'$, which slide laterally through and are maintained in position by boxes $b\ b'\ b'$, bolted upon the upper side of the bridge A. In the ordinary mode of construction all these boxes, 25 as well as the two bars $a\ a'$, are rectangular in section; but in my improvement only the rear bar and boxes are thus formed, the forward bar and boxes being cylindrical, so as to allow of rotation, for reasons to be hereinafter explained. At or near the center of each of 30 these horizontal bars is a pin or stud, $c\ c'$, hanging vertically downward, forming part of or being rigidly secured to the same. The lower extremity of these pins or studs is enlarged in the shape of a collar at $d\ d'$, and serves 35 as a support for the grip cross-head B.

The parts above described being old and well-known in the art, and arranged as stated, for the purpose of allowing lateral play for the 40 grip-shank, form no part of my improvement, save as regards the cylindrical shape given to the forward bar, a .

An arm or lever, C, forming part of the bar a , projects upward at right angles thereto and 45 at a slight angle from the vertical, the inclination being toward the forward end of the car. To the extremity of this arm is pivoted one end of a connecting-rod, D, the other end being similarly secured to a hand-lever, E, 50 upon the platform of the car at a point sufficiently distant from the fulcrum of the latter to secure the required amount of travel.

The releasing hand-lever E, which I find it convenient to make in all respects similar to 55 the ordinary hand-lever in use for controlling the grip, is pivoted to a projection, p , beneath, and oscillates within a slot in the plate P, secured to the front platform. Upon this plate P the brake and grip levers $E'\ E''$ are also pivoted and oscillate in a similar manner, thus 60 being in close juxtaposition to the releasing-

lever E, so that the latter may be instantly at command when needed. A pawl, F, upon the lever E is pressed downward by a spring, G, and is raised by the action of a hand-piece, H, 70 forming part of the handle, in the ordinary manner.

The construction of the levers controlling the grip and brake mechanism and their function are so well understood that it is not 75 deemed necessary to enter further into their description. I will therefore confine myself to the description of the lever E, which I term the "releasing-lever." This lever is bifurcated at its lower end and straddles a plate, K, corresponding to the serrated arcs or racks provided for the other two levers. Between the two arms thus formed the pawl F swings freely and is pressed down upon the plate K by the spring G. The upper edge of the plate 80 K forms an arc, the pivotal point of the lever E being the center thereof and is indented with a single deep notch, L, near its upper extremity, the rest of the arc being smooth and free from indentation. Into this notch L the 85 pawl F is pressed by the spring G when the hand-lever E is in its normal or vertical position.

The bell-crank lever m of the grip is provided at its upper extremity with a pin, n , 90 which engages with a two-pronged weighted hook, M, upon the rod N, which connects the gripping mechanism with the hand gripping-lever E' upon the front platform. When the rod N is raised sufficiently for the downward-projecting prongs of the weighted hook M to 95 clear the pin n , all connection between the grip, grip-frame, and mechanism contained therein, on the one hand, and the "actuating mechanism," by which term I designate the hand-lever 100 upon the platform and the rod which connects it with the grip proper, on the other hand, is severed.

The cylindrical bar a , which carries the arm C, is also provided with a projecting arm, O, 105 immediately beneath the gripper-rod N, which is of sufficient width to remain under said rod during all possible lateral oscillations imparted to the grip by irregularities or diversities from the normal line of the cable-conduit slot. This arm O, which may be in the form of a yoke or plate, is placed at such an angle relatively to the gripper-rod N and the arm C as to enable it to raise the rod N and its two-pronged weighted hook M clear of the 110 pin n when the arm C is oscillated backward to its extreme position. As the arms C and O and the supporting pin or stud c are all rigidly connected with the axial bar a , it follows that any oscillation imparted to one of 115 these members will be simultaneously communicated to the other two.

The upper part of the grip-frame or cross-head is extended longitudinally, and the extremities, instead of terminating in eyes for 120 the reception of vertical pins or studs standing upon the laterally-sliding bars, which is the

common form of construction, are bifurcated in the direction of the longitudinal axis of the grip, as shown in section at S in Fig. 6, Sheet 2, which enables it to straddle the pins $c c'$, 5 which I place beneath the laterally-sliding bars, the grip cross-head resting upon collars or flanges formed upon the lower extremities of the said dependent pins or studs, as heretofore described.

10 A modification in the form of construction of the guard-netting at the front of the car, corresponding to the cow-catcher of the locomotive, has been rendered necessary. It simply consists in providing an opening therein 15 at T of sufficient width and height to allow the free passage of the grip when it is released from the car and carried along by the cable. This opening is covered by a swing-door, V, of suitable design to conform with the rest of 20 the netting. This door laps over the edges of the opening on the outside and can only open outwardly, when, having allowed the passage of the grip, it falls back into place by reason of its weight. As the operation of my invention 25 depends for its success upon immediate action, and as the hand-lever which controls it is to be employed in lieu of the ordinary gripping-lever and in connection with the brake, it is best that the lever E, which actuates the 30 releasing mechanism, should be adjacent to or within instantaneous reach of the operator or gripman in charge. To this end I prefer that the three levers should be mounted upon a single plate, P, provided with lugs $t t t$ upon 35 its upper surface. Between these lugs, which are in pairs, are bolted the segmental racks which receive the paws of their respective levers, the racks of the gripping and brake levers being serrated in the usual manner, 40 while that of the grip-detaching lever is provided with only one notch, as already described. The upper ends of the racks are firmly bolted to the bed-plate. Three rectangular openings are cored out in the bed-plate 45 beneath the racks of sufficient width to admit of the free passage of the levers and of sufficient length to permit their full oscillation. Upon the under side of the plate are cast or forged hangers corresponding and on the same 50 vertical plane as the racks above described, said hangers terminating in bearings at their lower extremity, through which a spindle passes, serving as a common fulcrum for the three levers.

55 The operation of my device is substantially as follows: When it is necessary to instantly stop the car and the gripper-lever refuses to move or fails to effect the relaxing of the jaws of the grip, or the grip has become entangled 60 in the strands of the cable, so that it cannot free itself, the gripman instantly reverses the hand-lever E to the position shown in dotted lines, Fig. 3. This movement is transferred through the rod D, pivoted to the lever E at 65 f, to the arm C upon the sliding bar or shaft α , which is oscillated to the position shown in

dotted lines at C'. This causes a partial rotation of the bar α and an oscillation of the pin or stud c from beneath the cross-head which it supported. Simultaneously the arm O, forming part of the rotating bar α , is oscillated upward, so as to throw the two-pronged hook M free of the bell-crank lever upon the grip. The altered position of the parts are all indicated by dotted lines, Fig. 3. When this movement has taken place, it follows that the grip-frame, unsupported at one end, pulled away from its other support by the action of the cable, falls of its own weight upon the flanges of the slot of the conduit, as indicated 80 by the dotted lines at B', and is dragged away by the cable through the opening in the cow-catcher, the gate of which, V, yields to its passage and then falls back into place. Simultaneously with the reversal of the grip-detaching hand-lever E, the gripman also applies the brake by reversing the brake hand-lever E", and the progress of the car is effectually checked.

Although I have described at some length 90 what I deem to be the most convenient mechanism for releasing the grip from its supporting frame-work when it is desired to sever it from the car, yet other mechanical devices will suggest themselves, and I do not wish to 95 limit myself to any particular form of mechanism.

Having thus described my invention, I claim—

1. In a car propelled by a cable, the combination of a cable-carrying grip, a frame for supporting the grip, and the mechanism for entirely disconnecting the grip simultaneously from the frame and the car, as and for the purpose set forth. 100

2. In a cable car, the combination of the grip supported by two cross-bars, and the mechanism, substantially as described, for unlocking the grip from its supports, as and for the purpose set forth. 105

3. In a cable car, the combination of the grip cross-head B, the extremities of which are bifurcated and straddle the dependent supporting-pins $c c'$, and the releasing mechanism by which one of these pins can be moved from its supporting position, as and for the purposes set forth. 115

4. In a cable car, the combination of the bifurcated grip cross-head B, the rotary bar α , the pin c , and suitable mechanism for rotating the bar α , substantially as described. 120

5. In a cable car, the combination of the bifurcated grip cross-head B, the rotary bar α , the projections O, C, and c , the lever E, and connecting-rod D, as and for the purpose set forth. 125

6. In a cable-grip, the pin n on the bell-crank of the grip, in combination with the hooks M at the end of the rod N, as and for the purpose set forth. 130

7. In a cable car, the lever E, connected by the rod D with the arm C upon the rotating

bar *a*, which bar carries also the projection *O*, the upward movement of which disengages the rod *N* from the bell-crank lever *m*, and also carries the pin *e*, having a flange at its 5 lower end, upon which rests the bifurcated forward end of the grip cross-head *B*, all combined substantially as described.

8. The swing-door *V* at the center of the

cow-catcher of a cable car, in combination with a releasable grip, as and for the purpose 10 described.

ANDREW D. WHITTON.
